TREATMENT OF HYDROCARBON GASES

Hans Tropsch, Chicago, Ill., assignor to Universal Oil Products Company, Chicago, Ill., a corporation of Delaware

Application June 22, 1934, Serial No. 731,796

2 Claims. (Cl. 196—10)

This invention relates more particularly to the treatment of hydrocarbon gas mixtures containing substantial amounts of olefins such as, for example, those produced as a by-product in the cracking of the heavier portions of petroleum to produce gasoline. The process is particularly adapted to the treatment of the hydrocarbon gas mixtures obtained from the stabilizers of cracking plants and containing relatively high percentages of 3 and 4 carbon atom olefins.

In a more specific sense the invention has reference to a process for manufacturing gasoline boiling range hydrocarbon liquids from olefin containing hydrocarbon gas mixtures by a succession of cooperative steps involving both polymerization and pyrolysis as will be hereinafter disclosed in detail.

The fixed gases produced in the cracking of petroleum have at present only a limited value as fuel for the process or for other portions of the refinery in which the cracking plant is one unit. While the reactive olefinic content of these gases which comprises, for example, ethylene, propylene, butylenes, etc., has been utilized to some extent to manufacture, for example, hydroxy derivatives such as the corresponding alcohols and glycols, attempts to convert the gases into economic yields of gasoline have been only partly successful and it is with improvements in processes of this character that the present invention is concerned.

In one specific embodiment the present invention comprises treatment of cracked stabilizer gases, particularly to produce yields of gasoline boiling range liquids therefrom, by first subjecting the gas mixtures to contact with solid phosphoric acid catalysts to polymerize the olefinic constituents, cooling and separating the liquid polymers from the residual gases, re-cracking the residual gases to produce further quantities of polymerizable olefins, separating the 3 and 4 carbon atom hydrocarbon fractions from the cracking step and returning said fractions to further treatment in the primary polymerizing stage.

The character of the invention will be developed more in detail in connection with the attached drawing which shows diagrammatically in side elevation and by the use of conventional figures the interconnected elements of a plant in which the process may be conducted. The drawing is not to scale and the process may employ apparatus involving modifications which depart therefrom to a considerable degree so that the invention is not limited by the partic-

ular drawing or the description given in connection therewith.

Referring to the drawing cracked or other distillates to be stabilized may be introduced to a stabilizer unit through a line 1 containing control valve 2 to be taken by a pump 3 and discharged through line 4 containing control valve 5 to pass into and through a heating element 6 suitably arranged to receive heat from a furnace 7. During passage through the heating element the products are brought to a suitable temperature for effecting their stabilization usually somewhere within the range of 225 to 275° F., the stabilizer being commonly operated at from 100 to 150 pounds per square inch. Liquid 10 produced at a later stage in the process which is also subjected to stabilization enters line 4 from line 59. The production of this liquid material will be described at a later point in proper sequence.

10 represents a stabilizer of suitable design and capacity in which the top temperature is usually maintained at from 100 to 150° F., and the bottom temperature in the neighborhood of 325° F., by means of the usual refluxing and re-boiling operations, the details of which are omitted from the drawing as constituting no special feature of the present invention. The heated products from the primary element pass through a line 8 containing control valve 9 to 20 enter stabilizer 10 at a predetermined level. The stabilized material leaves the bottom of the stabilizer by way of line 11 containing control valve 12 and flows to receiver 13 which has a fixed gas release line 14 containing control valve 15 and a liquid draw line 16 containing control valve 17. The gases vented from receiver 13 will contain only very small amounts of 3 and 4 carbon atom hydrocarbons in the normal operation of the process. The liquid formed at this 30 point may be reserved for blending with the other gasoline boiling range liquids produced at succeeding stages in the process.

The overhead vapors from stabilizer 10 pass through a line 18 containing control valve 19 45 and may conveniently be brought up to the optimum temperature for polymerizing the more reactive olefins in the presence of the preferred catalyst by heat exchange with the hot products from the secondary or cracking step, receiving 50 this heat during passage through a heat exchanger 20. In case the heat supplied by the hot cracked products is more than necessary to raise the gases to the required temperature, a certain amount of them may be by-passed around the 55

heat exchanger through line 18' containing valve 19' which unites with exit line 21 containing control valve 22, the gas line then passing to polymerizer 23. The materials used in this polymerizer are of a special character and will be described in some detail.

The preferred catalytic contact materials comprise granular masses consisting of sized particles containing phosphoric acids adsorbed in relatively inert porous spacing or supporting materials such as, for example, ground pumice, fuller's earth, clays such as bentonite and Montmorillonite, kieselguhr or diatomaceous earth, artificially prepared silica gels, etc. In making up catalysts of this character any of the acids in which phosphorus has a valence of 5 (that is, ortho, pyro and meta phosphoric acids) may be employed in the original mixture or be present in the final composite particles. The manufacture of a catalyst using orthophosphoric acid and kieselguhr as the adsorbent is characteristic and the details of its manufacture which will be described in the following paragraph may be followed quite generally when using other acids and other types of adsorbents with due regard to the porosity, fineness, and chemical composition of the adsorbent, particularly in regard to its free and combined water content.

A composite catalyst material which is effective when polymerizing gaseous olefins may be made by mixing approximately 80% by weight of 90% orthophosphoric acid (75 to 100% strength may be employed) with about 20% by weight of diatomaceous earth after which the ingredients are thoroughly mixed and ground together to produce a mass of uniform consistency, particularly in respect to the distribution of the phosphoric acid. The mixed material is next carefully heated at temperatures from about 220 to 300° C., for a considerable period of time, usually 24 to 60 hours until, due to the loss of water from both acid and adsorbent, a solid cake is produced which has the required chemical composition and physical properties. This cake is then ground out of contact with moist air to produce particles which are screened and sized for the production of material of from approximately 4 to 30 mesh which serves as filler for treating towers or polymerizers.

It has been found feasible to start with pyrophosphoric acid in making up the composite catalysts and in this case temperatures of from about 160 to 200° C., are employed in the primary mixing stage and while the same temperatures as those employed when starting with orthophosphoric acid are used in the heating or drying period, the time necessary is considerably shortened and may be considerably less than 24 hours. In the heating period which leads to the formation of the solid cake the original phosphoric acid is partially dehydrated and it is probable that the final contact particles contain principally pyrophosphoric acid and a small amount of the meta acid.

The solid contact materials are represented in the drawing as occupying a central zone 24 in polymerizer 23 and dividing the interior of the polymerizer into upper gas space 25 and lower gas-vapor space 26. The temperatures and pressures employed in the polymerizer will vary with the composition of the entering gas mixture though as a rule the exact temperature employed will fall within the range of 250 to 550° F. (400 to 450° F. includes most of the commonly used temperatures) and the pressures are moderately

superatmospheric of the order of from 100 to 300 pounds per square inch.

Downflows are usually preferable on account of the washing action of the gases on the solid particles. The rate of flow is adjusted, along with the temperature and pressure to obtain a maximum of gasoline boiling range polymers.

Gases and vapors leave polymerizer 23 by way of line 27 containing control valve 28 and pass through a cooler 29 which is so regulated that preferably only gasoline boiling range liquids are condensed and substantially all of the 3 and 4 carbon atom hydrocarbons including propane, propylene, butane and the butenes are left in gaseous phase. A sharp separation at this point may require equipment somewhat more complicated than that shown in the drawing and this may be employed if necessary for the efficient operation of the process. The fixed gases and condensed liquids enter receiver or separator 32 and the liquids may be withdrawn through line 35 containing control valve 36 to storage or directly to blending with stabilized products. The gases from separator 32 are now preferably subjected to pyrolysis for the production of further quantities of olefinic gases, though if desired a certain portion of these gases may be withdrawn for other purposes through line 33 containing control valve 34. The bulk of the gas production passes through line 37 containing control valve 38 to pump or compressor 39 which discharges the gases through line 40 containing control valve 41 into and through a tubular cracking element 42 positioned in a furnace 43. The temperatures employed in the gas cracking coil are usually of the order of from 650 to 750° C., and the pressure is in the neighborhood of 150 pounds per square inch. The contact time in this cracking element is preferably varied so that considerable yields of higher olefins are obtained without the formation of any substantial amounts of gasoline boiling range material. The following table shows the approximate contact times which have been found favorable in most cases for thus producing higher olefins at temperature ranges within those specified.

Temperature vs. contact time

Degrees centigrade	Seconds
650	25
700	6
750	1

The heated and partially cracked gases leave the heating element by way of line 46 containing control valve 45 and pass through heat exchanger 20 previously described wherein their temperature is reduced by indirect contact with primary stabilizer gases. The partly cooled cracked gases leave the heat exchanger by way of line 46 containing control valve 47 and pass through a condenser 48 which may be maintained at temperatures below ordinary atmospheric to insure the effective liquefaction of the hydrocarbons of 3 and 4 carbon atoms to the molecule, since the object of this condenser is to make these compounds available in liquid form for recycling to the stabilizer and separate them from methane, ethane, ethylene and hydrogen. Line 49 containing control valve 50 represents the condenser 48 rundown line which leads to receiver or separator 51 which has a gas release line 52 containing control valve 53 for the removal and ultimate disposal of the lighter fixed gases mentioned and a liquid draw line 54 containing control valve 55

for drawing off any portion desired of the liquids produced at this point.

The major portion of the liquids is preferably recycled to pass through the stabilizing and the following polymerizing unit, line 56 containing control valve 57 leading to recirculating pump 58 which discharges the liquids back to line 4 by way of line 59 containing control valve 60.

10 By utilizing different stabilizer gas mixtures as charging stock and varying the conditions of operation within the ranges specified, the results of numerous runs, both of an experimental and a plant character could be introduced to illustrate the advantages of the invention but the following example is sufficiently characteristic to indicate its possibilities.

The gas mixture charged was obtained from a stabilizer operating in connection with a residual cracking plant, and contained 25% of propylene and 9.5% of butylenes, the remainder of the components of the mixture being principally paraffinic although ethylene was present in a small percentage. The gas mixture was first treated to polymerize the olefin content by passing it at a temperature of 410° F., and a pressure of 150 pounds per square inch over a solid composite catalyst mixture comprising about 60% by weight of pyrophosphoric acid supported upon a kieselguhr base. By this operation there was produced 6 gallons of liquid per 1000 cubic feet of gas charged, corresponding to substantially complete removal by polymerization of the olefins of 3 and 4 carbon atoms. The properties of the liquid produced are shown in the table below:

Properties of polymerized liquid

Dissolved gas.....	per cent	12
Gasoline fractions 100 to 437° F.....	do	87
Higher boiling polymers.....	do	1
Blending octane number of gasoline fraction.....		112
Total sulphur.....	per cent	0.10

45 The residual gases from the first step of the process were then subjected to pyrolysis to produce olefins which are ultimately polymerized to form additional yields of gasoline. The temperature employed in the secondary cracking 50 step is 1300° F., under a pressure of 100 pounds per square inch, a time of reaction being allowed

of the order of about 6 seconds. By cooling to approximately 32° F., the 3 and 4 carbon atom hydrocarbons comprising essentially propane, propylene, butanes, butenes, and some traces of higher boiling compounds are separated as a liquid and returned to the primary stabilizer.

The total yield of gasoline produced by the foregoing operation is 9 gallons per 1000 cubic feet of stabilizer gas charged and indicates that the process is capable of considerably augmenting the yield of gasoline from the cracking process. In addition it will be noted that the octane number of the products is of a high order so that they are of special value for blending with gasolines which are inferior in this respect.

The foregoing specification and example have sufficiently disclosed and exemplified the invention, but neither is to be construed in the light of imposing undue limitations therein.

I claim as my invention:

1. A process which comprises stabilizing cracked gasoline distillate to separate gaseous olefins from the gasoline, contacting the thus separated gas with a polymerizing agent to produce gasoline-boiling hydrocarbons therefrom, 25 separating the latter from residual gases, cracking the residual gases by heat treatment to produce polymerizable olefins therefrom, cooling the cracked products to separate the polymerizable olefins therefrom as liquid, and supplying said 30 liquid to the aforesaid stabilizing step whereby it is revaporized therein and passed through the polymerizing operation together with the gaseous olefins separated from said distillate.

2. A process which comprises stabilizing cracked gasoline distillate, thereby forming a stabilizer gas consisting essentially of 3 and 4 carbon atom olefinic and paraffinic hydrocarbons, subjecting the fresh stabilizer gas to a polymerization treatment to polymerize the olefinic 40 content thereof into normally liquid hydrocarbons, separating the latter from the residual paraffinic hydrocarbons, cracking the residual paraffins to produce 3 and 4 carbon atom olefins therefrom, separating the latter as liquid from 45 gaseous cracked products of lower molecular weight, and supplying said liquid to the aforesaid stabilizing step whereby it is revaporized therein and passed through the polymerization treatment together with the fresh stabilizer gas.

HANS TROPSCH.
